BOMB DISMANTLING APPARATUS

Willard G. Axtell, Los Angeles, Calif., and
George H. Todd, Pine Bluff, Ark.

Application November 20, 1945, Serial No. 629,894

2 Claims. (Cl. 86—36)

(Granted under the act of March 3, 1883, as
amended April 30, 1928; 370 O. G. 757)

1

The invention described herein may be manufactured and used by or for the Government for governmental purposes, without the payment to us of any royalty thereon.

This invention relates to devices for handling bombs and particularly to an instrumentality for the disassembly of incendiary bombs.

The primary object of the invention is to provide a method and a device wherein the handling of the bombs is effected with minimum of hazard.

A further object is to provide a device for safe removal of the primer and firing pin assemblies from incendiary bombs by non-mechanical means.

Still another object of the invention is to provide means for safe removal of the primer and the firing pin assemblies from incendiary bombs wherein the actual "blow-out" is effected by a column of air or inert gas which is actuated ahead of a column of high pressure water. This air column added the expansive force needed to overcome the difficulty heretofore present in previous devices for performing similar operations.

More specifically the invention contemplates a compact instrumentality comprising a vise-like element, one side of which is fitted with a cone nozzle for supplying high-pressure for the actual "blow-out" operation.

This device is primarily designed to reclaim the so-called rejects during the manufacture of the bomb as well as for final dismantling of the bomb stocks.

With these and other objects in view this invention consists in certain details of construction and combinations and arrangements of parts, all as will hereinafter be more fully described and the novel features thereof particularly pointed out in the appended claims, considered in the light of the accompanying drawing which forms a part thereof, wherein, the single figure is a schematic view partly in section of the preferred embodiment of the device for disassembly of incendiary bombs.

In the disassembly of incendiary bombs it is necessary to remove the firing pin assembly and the primer assembly, which are cemented together into the bomb case. Any purely mechanical means for doing this is necessarily hazardous to the operating personnel.

The device of this invention removes both assemblies quickly and with a minimum amount of hazard.

In actual use the incendiary bomb 10 is held fast in vise like elements 11 and 12 specifically

2

shaped to accommodate the bomb-end containing the firing pin and the primer assembly in the upright position shown. The element 12 is stationary while the element 11 may be movable by either pneumatic or hydraulic means 13 operable by a 4-way valve 14, which may admit either compressed air or the liquid from the source of supply indicated by an arrow through the pipe 15 into the right or left ports of the hydraulic means 13.

The bomb 10 is placed against the collar ledge 16 of the vise so as to align the space having a vent hole 17 in the incendiary bomb with the nozzle 18 through which the air column entrapped in chamber 22 and the high pressure water through valve 20 can be admitted. A T-connection shown at 19 is provided at one end with a quick-opening release valve 20 (normally closed) while the other end is fitted with 20 a quick opening valve 21 (normally open).

It will be noted that the pipe 22 affords an air column of approximately three cubic inches to provide the expansive force to loosen and to blow out the firing pin and the primer assembly.

The three valves 20, 21 and 14 are arranged to operate together by means of a common lever arm 23 properly interconnected with each valve so that the valve 14 will open the vise when the high water pressure valve 20 is closed and the exhaust valve 21 is open.

After the bomb is placed against collar ledge 16 in the vise, the valves are moved so as to close the vise and admit high pressure water at the bottom of the air-column in the pipe 22, thus forcing the air column entrapped in chamber 22 through the nozzle 18 into the space between the first-fire mix 24 and the primer assembly 25.

As the assemblies (primer assembly 25 and firing pin 26) are dislodged by this high pressure, the expansive force of the air compressed above then blasts them out and the high pressure water immediately following the air column floods the first-fire mix 24 and washes out any loose powder.

The valves are now moved to "off" position and the device is ready to repeat the cycle.

The time required for a complete cycle is about five seconds, the greater amount of this period being consumed in allowing the water to drain from the air column.

Since the bombs are provided with two or three vent holes, suitable plugs are placed in the vise sections 11 and 12 away from the cone nozzle 18.

Thus it is seen that a device is produced for

the safe removal of dangerous parts of incendiary bombs. Also the high pressure water soaks the highly inflammable filling thus making it reasonably safe in the dismantling operation of bombs.

We claim:

1. Means for removing the firing pin and primer assemblies from incendiary bombs of the type wherein the main incendiary charge is disposed in one end of the bomb body, while the firing pin and primer assemblies are cemented in the other end and separated from the incendiary charge, and wherein there is at least one vent hole in the bomb body intermediate the incendiary charge and the firing pin and primer assemblies, which comprises in combination, a nozzle, vice means carrying said nozzle and being adapted for gripping said bomb body and for holding said nozzle in fluid-tight registration with the vent hole of the aforesaid type, an air chamber connected with said nozzle, means for connecting a source of water pressure to said air chamber, and means for draining water from said air chamber.

2. Apparatus for removing the firing pin and primer assemblies from incendiary bomb of the type wherein the main incendiary charge is disposed in one end of the bomb body while the firing pin and primers are cemented in the other end and separated from the incendiary charge, and wherein there is at least one vent hole in the bomb body intermediate in the incendiary

charge and the firing pin and primary assemblies, said apparatus comprising in combination a first valve-operated gripping means for holding said projectile; means providing a chamber containing a column of air; nozzle means connecting said column of air with said aperture; a second valve means operatively connected to said chamber and arranged to permit the entrance of a quantity of liquid under high pressure behind said air column sufficient to compress said air column and force it through said nozzle and said aperture ahead of said liquid; a third valve means for subsequently exhausting said liquid from said chamber; means for the concurrent operation of said three valve means arranged so that when said second means is closed the other two will be opened and conversely when the said second means is opened the other two will remain closed.
